CLAIM

The ornamental design for a knife handle, as shown and described.

DESCRIPTION

FIG. 1 is a right front bottom perspective view of a knife handle, showing our new design;

FIG. 2 is a left rear bottom perspective view thereof;

FIG. 3 is a left rear top perspective view thereof;

FIG. 4 is a right front top perspective view thereof;

FIG. 5 is a right side view thereof;

FIG. 6 is a left side view thereof;

FIG. 7 is a top perspective view thereof;

FIG. 8 is a bottom perspective view thereof;

FIG. 9 is a front magnified view thereof;

FIG. 10 is a rear magnified view thereof; and,

FIG. 11 is a right side cross-sectional view, taken along and in the direction of Line 11-11 in FIG. 7. The broken lines illustrate environmental structure that form no part of the claimed design.

Those portions shown with dashed lines are for illustration purposes only, forming no part of the claimed ornamental design.

1 Claim, 8 Drawing Sheets(56)
